(57) **CLAIM**

We claim, the ornamental design for a railway vehicle, as shown and described.

DESCRIPTION

1.1: Perspective view;

1.2: Front view;

1.3: Front view with a lid of foot-plate open featuring callout region 7;

1.4: Rear view;

1.5: Side view;

1.6: Top view; and

1.7: Enlarged view of callout region 7.

A control car of an electric multiple unit of a streamlined shape that comprises a driver's cabin with a nose extended forward, a body of the passenger compartment located on a frame mounted on bogies with wheel pairs; the rear end part thereof contains a transitional vestibule.

In the drawings, the broken lines represent portions of the railway vehicle that form no part of the claimed design. In the drawings, the dash dot broken lines in FIGS. 1.3 and 1.7 represent boundaries of the enlarged portions and form no part of the claimed design.
